UNITED STATES PATENT OFFICE.

GEORGE E. SMITH, OF EXETER, NEW HAMPSHIRE.

NON-REFILLABLE BOTTLE.

SPECIFICATION forming part of Letters Patent No. 597,030, dated January 11, 1898.

Application filed February 18, 1897. Serial No. 624,026. (No model.)

To all whom it may concern:

Be it known that I, GEORGE E. SMITH, a citizen of the United States, residing at Exeter, in the county of Rockingham and State of New Hampshire, have invented certain new and useful Improvements in Non-Refillable Bottles; and I do hereby declare the following to be a full, clear, and exact description of the invention, such as will enable others skilled in the art to which it appertains to make and use the same.

My invention relates to improvements in what are known as "non-refillable" bottles, or bottles in which after once being filled and then emptied their identity will be destroyed, so that they cannot be refilled without being at once detected, thereby affording protection to manufacturers of proprietary liquors against the fraudulent use of their bottles by imitators of their goods.

The invention consists in the novel construction and combination of parts hereinabove fully described and claimed.

In the accompanying drawings, Figure 1 is a horizontal sectional view, partly in elevation, of the upper portion of a bottle constructed in accordance with my invention and with my improved means for sealing or closing the same. Fig. 2 is a horizontal section on the line αx , Fig. 1. Fig. 3 shows a plan and an edge view of the disk, which rests upon the ribs in the neck of the bottle. Fig. 4 shows a plan and an edge view of the closing-ring before being inserted in the neck of the bottle and also a plan view of the same after being spread into annular form. Fig. 5 is a longitudinal section of a modified construction. Fig. 6 shows a plan and edge view of the disk. Fig. 7 is a plan view of a closing sleeve or bushing which rests upon said disk. Fig. 8 is a longitudinal sectional view of another modification. Fig. 9 is a longitudinal sectional view showing the stopper and the yoke connecting it with the disk. Fig. 10 is an elevation of an instrument for spreading the corrugated ring.

In the said drawings, referring now to Fig. 1, the reference-numeral 1 designates a bottle, 2 the neck thereof, and 3 the mouth.

Formed in the interior of the neck 2 is an annular groove 4, with an intersecting groove 5 above the same, forming a shoulder 6.

Just below the groove 4 are a number of ribs or flutes 7, the upper ends of which form the lower side of the said groove. Seated upon said ribs is a thin circular plate or disk 8, of metal or other suitable material, which is inserted in place during the manufacture of the bottle and is of a diameter sufficient to allow the periphery to engage with said groove, so that it cannot be removed therefrom without exerting sufficient force to destroy its identity. Seated upon said disk is an annular ring 9. This ring, before being inserted in place, is in the form of the corrugated ring shown in the views at the left, Fig. 4, so that it will be small enough in diameter to be pushed down into the neck onto the disk, where it is spread outward by the tool shown in Fig. 10, so that it will assume the circular or annular shape shown in Figs. 1 and 4.

The tool shown in Fig. 10 comprises a rod 10, provided at the upper end with a head 10^a and at its lower end is formed with a number of radial lugs 11, to which are pivoted the inclined fingers 12, the lower portions of which are made straight and provided at the ends with ears 13. The numeral 14 designates a circular slide embracing the upper portions of the fingers and provided with finger-holds 15. A coiled spring 16 is interposed between the head 10^a and the slide 14.

The operation is as follows: The disk 8, as before stated, is inserted in place when the bottle is being made, and being smaller in diameter than the neck of the bottle there will be a space between its periphery and the interior of the neck, the ribs or flutes 7 holding it in place and preventing it from dropping down into the bottle. The bottle is now filled, when the corrugated ring is dropped into the neck and falls down upon the disk. The tool shown in Fig. 10 is then inserted in the neck and the slide 14 pulled up, which will contract the upper ends of the pivoted fingers 12 and expand the lower ends, and the ears engaging with the inwardly-projecting corrugations of the ring will press them outward, causing the ring to assume the circular or annular form shown in Fig. 1. This ring when thus spread out will be of smaller diameter than the disk and, fitting against the shoulder 6, will close the openings between the disk and bottle-neck and prevent the contents of

the bottle from being withdrawn. To withdraw the contents of or empty the same, a stick, rod, or other instrument is inserted in the neck and the disk pushed into the bottle. 5 After thus being pushed into the bottle the disk cannot again be put in place nor can a new one be inserted in the groove.

In the modification shown in Figs. 5, 6, and 7 instead of employing the corrugated ring I 10 use a sleeve or bushing 17 in lieu thereof, which is cemented in place above the disk when the bottle is filled. The operation is the same as that before described.

In the modification shown in Figs. 8 and 9 15 the ring or sleeve is dispensed with and the disk is secured to a vertical arm 18, connected at its upper end with a longitudinal arm 19, the ends of which are bent upwardly and then inwardly and engaged with a cork or stopper 20. In pulling out the cork the disk is with-

drawn with it and cannot be again inserted in place.

Having thus fully described my invention, what I claim is—

The combination with a bottle having two intersecting annular grooves of different diameters in the inner side of the neck and a series of ribs forming the lower side of the larger and lower groove, of the disk of smaller diameter than said lower groove seated on 30 said ribs and the corrugated ring inserted in the neck and seated on said disk and then spread into circular form to engage with the upper groove, substantially as described.

In testimony whereof I affix my signature 35 in presence of two witnesses:

GEORGE E. SMITH.
